UNITED STATES PATENT OFFICE

GEORGE A. HOLMES, OF NEWTON, MASSACHUSETTS, ASSIGNOR TO UNITED-CARR FASTENER CORPORATION, OF CAMBRIDGE, MASSACHUSETTS, A CORPORATION OF MASSACHUSETTS

PIN FASTENER

Application filed January 9, 1932. Serial No. 585,755.

My invention aims to provide improvements in pin fasteners particularly adapted for use in connection with the attachment of slip covers.

5 In the drawing, which illustrates a preferred embodiment of my invention:

Figure 1 is a front elevation of the pin;
Fig. 2 is a rear elevation of the pin;

10 Fig. 3 is a side elevation of the pin as it appears in unattached position; and

Fig. 4 is a section through an installation showing the pin in attached position.

The particular pin selected for illustration is of the "campaign button" type but having a hinged plate whereby attachment and detachment of the pin is made easier. I am aware of the fact that hinged pins of the general type shown are not new to me and therefore I shall describe and claim only that 20 which I consider my contribution to the pin fastener art.

My improved pin fastener comprises an attaching part A and a plate part B. The attaching part A is formed from a single piece of wire bent to provide a pair of spaced parallel legs 1-1 pointed at the lower ends and joined together at the upper ends by a connecting portion, as best shown in Fig. 2. The connecting portion is bent to provide shoulders 2-2 adjacent the legs 1-1 and a U-shaped loop 3 between the shoulders.

Any suitably shaped plate part B may be provided and it is preferably formed from sheet metal. At the upper edge of the plate 35 B and at the rear side I have provided a hinge portion 4 integral with the plate and engaged with the loop 3 thereby pivoting the plate for movement relative to the attaching part A. At the lower edge and behind the plate, I have provided two stabbing prongs 5-5 spaced from each other and located in such a manner as to be in alignment with the shoulders 2-2. These prongs 5-5 are bent to extend from the lower edge of the 40 plate B upwardly behind it and then outwardly in a generally curved manner, as best shown in Fig. 3. The outwardly extending portions are yieldable and so shaped that a detent 6 is provided in each so that 45 as the prongs pass either under the shoulders

2-2 or over (as illustrated), the shoulders engage in the detents 6-6. In this manner the plate part B is held in locked relation to the attaching part A.

To attach the pin fastener to an upholstered structure, such as shown in Fig. 4, the plate B is swung into an unlocked position at an angle to the attaching portion B. Thus the legs are forced through the material of the installation as shown. Thereafter the 55 plate is pressed toward the attaching part to force the sharp pointed stabbing prongs into the upholstery to prevent accidental withdrawal of the fastener. In this position the detents engage the shoulders and lock 60 the plate in position. The pin may be easily and quickly removed by simply pulling outwardly on the plate to unlock it and then pulling the fastener upwardly.

My improved pin fastener is simple and 70 easy to assemble. It has but a single hinge and yet it has two stabbing prongs for engagement with the material of the installation and two locking features, thus providing double the holding power of a single 75 pronged device.

While I have illustrated and described a preferred embodiment of my invention, I do not wish to be limited thereby, because the scope of my invention is best defined by the 80 following claims.

I claim:

1. A pin fastener comprising, in combination, an attaching part having a pair of spaced sharp pointed legs, a cross-bar connecting 85 said legs at one end, a plate part, a single hinged connection between said plate part and said cross-bar, a stabbing prong at each side of the hinged connection extending rearwardly from said plate between said legs and locking means provided partly by said stabbing prongs and partly by said cross-bar to hold said plate part in one position relative to said attaching part.

2. A pin fastener comprising, in combination, an attaching part having a pair of spaced sharp pointed legs, a cross-bar connecting said legs at one end, a plate part, a single hinged connection between said plate part and said cross-bar, a stabbing prong at 95 100

each side of the hinged connection extending rearwardly from said plate between said legs and locking means provided partly by said stabbing prongs and partly by said cross-bar
5 to hold said plate part in one position relative to said attaching part, said cross-bar being formed into two shoulders each adjacent to a pointed leg and a loop between said shoulders, said hinged connection comprising
10 a hinge portion on said plate part engaging said loop to pivot the plate part and said stabbing prongs being adapted to engage said shoulders for the purposes described.

3. A pin fastener comprising, in combination,
15 an attaching part formed from a single piece of wire bent to provide two spaced sharp pointed legs, a cross-bar connecting said legs at one end, two shoulders each extending at right angles from one leg of the attaching
20 part, a U-shaped loop formed in said cross-bar between said shoulders, a plate part formed from a single piece of metal and having concealed at the under side a hinge portion engaging said loop to pivot the plate to
25 the attaching part and two yieldable stabbing prongs extending away from the plate and adapted to enter the material to which the pin is to be attached and said stabbing prongs having detent means engaging said shoulders
30 to lock the plate in position when said stabbing prongs are in operating position.

In testimony whereof, I have signed my name to this specification.
